United States Patent Office

Des. 200,044
Patented Jan. 5, 1965

200,044

EMBROIDERED FABRIC, OR SIMILAR ARTICLE

Alvin A. Dubin, 432 Garden Blvd., Garden City, N.Y.

Filed Aug. 27, 1963, Ser. No. 76,366

Term of patent 3½ years

(Cl. 92—1)

The figure is a plan view of an embroidered fabric embodying my new design.

I claim:

The ornamental design for an embroidered fabric, or similar article, substantially as shown.
